UNITED STATES PATENT OFFICE.

HARVEY Z. KASSON AND ALEXANDER J. KASSON, OF GLOVERSVILLE, N. Y.

IMPROVEMENT IN GLOVES.

Specification forming part of Letters Patent No. 121,630, dated December 5, 1871.

To all whom it may concern:

Be it known that we, HARVEY Z. KASSON and ALEXANDER J. KASSON, of Gloversville, in the county of Fulton and State of New York, have invented certain new and useful Improvements in the Manufacture of Gloves and Mittens; and we do hereby declare the following to be a full, clear, and exact description of the same, reference being had to the accompanying drawing which forms a part of this specification.

Our invention relates to the construction of thumbs for gloves and mittens, said thumb being composed of two pieces, so cut as to be applied either to a round or oblong hole of a glove or mitten; the object being to give more strength and durability to the thumb, and to economize in cutting the leather and cloth.

Figures 1 and 2 are views of the two pieces composing the thumb of the glove or mitten, and Fig. 3, a front view of the glove, showing our improved thumb.

A and B are the two pieces composing the thumb of a glove or mitten. They are cut out by suitable dies in the forms shown in Figs. 2

and 3 of the drawing. They are then sewed together, the piece A forming the outside or top of the thumb and the piece B the front or inside of the thumb. When cut in the manner herein shown and described they can be applied either to a round or oblong hole of a glove or mitten; also there is quite a saving in the cutting of the leather and cloth used for the thumb, and the glove is found to be more durable. The thumb-pieces A and B, when cut as shown, give a graceful and easy-fitting shape to the thumb; and, moreover, throw the top or inside seam of the thumb, which is generally most exposed, to the outside, which is desirable. This seam is marked *c*.

What we claim is—

The thumb of a glove or mitten, composed of two pieces, cut, as herein shown and described, so as to be applied either to a round or oblong hole of a glove or mitten.

HARVEY Z. KASSON.

ALEXANDER J. KASSON.
